Primary Examiner — Mimosa De(74) *Attorney, Agent, or Firm* — Merek, Blackmon & Voorhees, LLC(57) **CLAIM**

The ornamental design for an elastic belt chair, as shown and described.

DESCRIPTION

FIG. 1 is a front elevational view of a first embodiment of our elastic belt chair;

FIG. 2 is a right side perspective view of the elastic belt chair shown if FIG. 1; with the left side perspective view being a mirror image thereof;

FIG. 3 is a right side elevational view of the elastic belt chair, with the left side elevational view being a mirror image thereof;

FIG. 4 is a rear elevational view of the elastic belt chair;

FIG. 5 is a bottom plan view of the elastic belt chair; and,

FIG. 6 is a top plan view of the elastic belt chair.
